ABSTRACT: A wig styling rack for mounting on a chair having a back, a seat, and a pair of spaced arms consisting of a central portion having a pair of laterally adjustable arms for resting on said arms of said chair, a downwardly depending adjustable leg mounted on said central portion for resting on said seat of the chair for preventing pivotal movement of said body portion in a first direction, a rearwardly extending arm mounted on said central body portion for resting against the back of said chair and thus preventing pivotal movement of said central body portion in a direction which is opposite to said first direction, and a frame member extending upwardly from said central body portion for mounting a wig form at the top thereof.

WIG STYLING RACK

BACKGROUND OF THE INVENTION

The present invention relates to an improved universal wig styling rack for mounting on practically all of the types of chairs which are normally used in beauty parlors.

By way of background, a wig as fabricated at the factory is not styled for any particular person but contains long straight hair. After the wig is purchased, the hair is styled by a hair stylist to meet the requirements of the purchaser. This styling includes the cutting of the hair to the correct length and thereafter setting the hair. In the past there were two ways of styling the wig. The first was to have the purchaser wear it during the styling. This constituted an inconvenience to the hair stylist as well as to the customer. Another way of styling the wig was to mount it on a form which was secured to a tabletop or the like by means of a clamp. However, this caused the wig to be in an unnatural position which prevented the stylist from working on the wig with the normal dexterity which she could utilize when working on a person who was sitting in a normal upright position in a chair. The unnatural work position not only affected the quality of the job but often caused backaches. In addition, since the wig was clamped in a fixed position on the table it had to be remounted frequently during the styling operation so as to permit the proper styling from various angles. It is with overcoming the foregoing deficiencies of the prior art that the present invention is concerned.

SUMMARY OF THE INVENTION

It is accordingly the primary object of the present invention to provide an improved wig styling attachment which can be mounted on a swivel chair of the type normally used in beauty parlors and which will position a wig in the same position as the head of a person sitting in the chair, thereby permitting a hair stylist to work on the wig in the same manner as she would work on a person sitting in the chair.

Another object of the present invention is to provide an improved wig styling attachment which is universally adjustable so that it can be mounted on practically any type of chair used in a beauty parlor as long as the chair has arms, a seat and a back.

A further object of the present invention is to provide an improved wig styling attachment which is lightweight so that it can be handled with ease and which is relatively simple in construction and easy to operate so that it can be used conveniently.

A still further object of the present invention is to provide an improved wig styling attachment which can be moved from chair to chair while a wig is mounted thereon so as to permit a wig to be moved to a chair under a dryer after the styling has been completed without actually touching the wig itself and thereby obviating the necessity to handle the wig and remount it on a wig form after it has been styled. Other objects and attendant advantages of the present invention will readily be perceived hereafter.

The improved wig styling attachment of the present invention includes a central body portion, a frame member attached to and extending upwardly from said central body portion for mounting a head form on which a wig is placed, first means secured relative to said central body portion for preventing pivotal movement of said frame member in a first direction, and second means secured relative to the central body portion for preventing pivotal movement of said frame member in a second direction which is opposite to said first direction to thereby hold said attachment in position on said chair against movement when external forces are applied to said head form incidental to the styling of a wig thereon. In its more specific aspects, the present invention includes arms extending laterally from the central body portion for resting on the spaced arms of a chair, a downwardly depending leg extending from said central body portion for resting on the seat of said chair, and a rearwardly extending arm attached to said central body portion for resting against the back of the chair. The at-

tachment is placed in position in the chair by merely resting it on the arms of the chair and adjusting the leg to rest firmly on the seat. This adjustment is effected by the loosening and tightening of a simple wing nut. In this manner the attachment can be mounted and removed from a chair in an extremely simple and expedient manner. The various aspects of the present invention will be more fully understood when the following portions of the specification are read in conjunction with the accompanying drawing wherein:

BRIEF DESCRIPTION OF THE DRAWING

FIG. 1 is a side elevational view of the improved wig styling attachment positioned relative to a chair on which it is mounted;

FIG. 2 is a front elevational view of the wig styling attachment of FIG. 1; and

FIG. 3 is a plan view taken substantially in the direction of arrows 3-3 of FIG. 2.

DESCRIPTION OF THE PREFERRED EMBODIMENT

The improved wig styling attachment 10 includes a central body portion 11 which is essentially an angle member having a vertical leg 12 and a horizontal leg 13. The ends 14 of vertical leg 12 are cut at an angle so as not to dig into the arms 15 of chair 16. A pair of arms 17 extend laterally from central body portion 11. Each arm 17 has a slot 18 therein which receives the shank of bolt 19, the head of which bears on the underside of horizontal leg 13. A wing nut 20 tightens each arm 17 in any desired adjusted position. The outer ends of arm 17 are formed into vertical flanges 21 which bear against the outer sides 22 of the chair arms 15 after arms 17 have been adjusted. Padding 23 is interposed between the chair arms and the portions of lateral arm 17 in contact therewith, padding 23 being secured by pressure sensitive adhesive or the like to the undersides of arms 17 and the inside of flanges 21. The padding 23, which may be of a suitable foam material or felt prevents slipping as well as preventing marring. The connection consisting of bolt 19 and slot 18 associated with arms 17 permits the arms 17 to be pivoted about the axes of bolts 19, to thereby cause flanges 21 to lie squarely against the outer sides of the chair.

In order to prevent rotation of central body portion 11 in a clockwise direction in FIG. 1 about the longitudinal axis of said central body portion, a leg 24 is adjustably attached to vertical leg 12 of central body portion 11 by means of bolt 25 extending through slot 26. A wing nut 27 secures leg 24 in any desired adjusted position after foot or flange 28 has been moved downwardly into engagement with seat 29 of the chair. Suitable padding 30, which may be the same material as padding 23, prevents foot 28 from slipping. It will be appreciated that leg 24 prevents the clockwise tilting of bracket 10 in the event a force is applied from left to right on wig head 31.

In order to prevent counterclockwise rotation of central body portion 11 in FIG. 1, a rearwardly extending arm 32 is attached to central body portion 11 by means of bolts 33. A flange 34 extends upwardly from arm 32 and bears against the back 16' of the chair 16. Suitable padding 35, which may be foam material or rubber, is cemented to flange 34 and prevents marring of the back of the chair as well as providing nonslippping frictional engagement therewith.

The wig head or form 31 on which the wig is mounted is in the shape of a human head and includes a central vertical aperture, not shown, which receives the end of mandrel 36 which extends upwardly from C-clamp 37 which is attached to inverted U-shaped frame member 38 having flanges 39 at the lower end of legs 40, said flanges 39 being attached to horizontal leg 13 of central body member 11 by means of bolts 41. The C-clamp 37 is attached to base 42 which extends between legs 40 and can be removed from said base 42 if required. The wig head or form 31 and the C-clamp 37 are conventional items which are normally found in beauty shops

and therefore the improved wig styling rack of the present invention can be furnished to beauty shops without C-clamp 37 and wig head 31.

The members 11, 17, 24 and 32 are fabricated from suitable lightweight aluminum, or the like.

It can readily be seen that the improved wig styling rack 10 of the present invention can be positioned on any type of beauty parlor chair having arms, a seat and a back. Once this rack has been adjusted for any size of chair, it need not be readjusted but may merely be placed in position by moving the entire rack as adjusted downwardly so that its lateral arms 17 rest on the arms of the chair. The foot 28 will automatically then be in a position on the seat of the chair and the flange 34 will rest against the back of the chair. During the wig styling operation the stylist stands behind the chair in the normal position which she would occupy when working on a live customer. As required, she may raise and lower the chair or may swivel the chair in order to obtain the best vantage point for effecting the styling. The operator will thus be able to work most efficiently and not be forced to assume awkward positions which would otherwise be required if she were working on a wig form attached to a bench or table.

After the styling has been completed, the entire rack 10 may be lifted off of the chair and be placed onto a chair situated underneath a dryer for final drying. There need be no handling of the wig during this process and therefore once it has been properly set it remains set until it is finally dried. During the time that the stylist is working on the wig, the wig styling rack 10 cannot move from side to side on the chair because flanges 21 of arms 17 bear against the sides of the chair, and furthermore it cannot tilt forwardly or rearwardly because of leg 24 and arm 32. The bearing of flanges 21 against the sides of the chair provides stabilization in addition to that provided by the above structure. Thus the present invention provides an extremely stable wig styling rack which may be conveniently placed on chairs of different dimensions which are normally found in beauty parlors.

While the present invention has been described with respect to wigs, it will be appreciated that it has equal applicability to hairpieces worn by men and can be used as an attachment to a

barber chair or any other type of chair which has arms.

I claim:

1. A wig styling attachment for mounting on a chair having a seat and a back comprising a central body portion, a frame member attached to and extending upwardly from said central body portion including means for mounting a head form, means for mounting said central body portion on said chair including downwardly depending leg means and means located at the lower end of said leg means for engaging said seat for preventing pivotal movement of said frame member in a first direction, and rearwardly extending arm means and means at the outer end of said arm means for engaging said back for preventing pivotal movement of said frame member in a second direction which is opposite to said first direction, 15 thereby to hold said attachment in position on said chair against movement when external forces are applied to said head form incidental to the styling of a wig thereon.

2. A wig styling attachment as set forth in claim 1 wherein said chair includes arms and wherein said means for mounting 20 said central body portion on said chair also includes second arm means extending laterally from said central body portion for resting on the arms of said chair.

3. A wig styling attachment as set forth in claim 2 wherein said leg means includes means for permitting said means 25 located at the lower end of said leg means to move in a vertical direction to thereby permit adjustment thereof for firm engagement with various chairs having different distances between the top of said arms of said chair and said seat.

4. A wig styling attachment as set forth in claim 2 including 30 means for extending said second arm means laterally relative to said body portion for adjustment to fit chair arms which are spaced varying amounts, and means at the outer ends of said second arm means for engaging the outer sides of the arms of said chair.

5. A wig styling attachment as set forth in claim 4 including means for permitting pivotal movement of said arm means about a substantially vertical axis to permit said means at the outer ends of said arm means to rest squarely against said outer sides of said arms of said chair.
